GIRDLE

Sallyann Z. Salisky, Garfield, N.J., assignor to International Playtex Corporation, Dover, Del., a corporation of Delaware

Filed Dec. 2, 1966, Ser. No. 4,900

Term of patent 14 years

Int. Cl. D2—02

U.S. Cl. D2—2

F 1 - 2

I claim:

The ornamental design for a girdle, as shown and described.
